UNITED STATES PATENT OFFICE.

DANIEL W. CRONIN, OF LITTLE ROCK, ARKANSAS.

LANTERN.

SPECIFICATION forming part of Letters Patent No. 479,247, dated July 19, 1892.

Application filed February 16, 1892. Serial No. 421,770. (No model.)

To all whom it may concern:

Be it known that I, DANIEL W. CRONIN, of Little Rock, in the county of Pulaski and State of Arkansas, have invented a new and useful Improvement in Lanterns, of which the following is a full, clear, and exact description.

My invention relates to improvements in hand-lanterns which are provided with glass globes to protect the flame, and has for its object to provide such a device with a central draft and return flues, which will increase the efficiency of the lamp by increasing its illuminating power and by rendering the combustion of the illuminant more perfect.

To these ends my invention consists in the peculiar construction of parts and their combination, as is hereinafter described and claimed.

Reference is to be had to the accompanying drawings, forming a part of this specification, in which similar letters of reference indicate corresponding parts in all the figures.

Figure 1 is a perspective view of the lantern. Fig. 2 is a side elevation in section on the line 2 2 in Fig. 3, and Fig. 3 is a plan view in section on the line 3 3 in Fig. 2.

The oil chamber or fount A is preferably made cylindrical, having the usual filler-hole, capped, as at a, and at the base a depending flared flange b is secured, which has a series of perforations c formed in it at spaced intervals. The center of the fount A is occupied by a cylindrical draft-tube d, which penetrates the bottom e of the fount and projects vertically through it, extending a suitable distance above to pass through the externally-threaded collar f of the fount and also through the burner-shell.

The burner consists of an external shell g, which is cylindrical and contracted below, having the lower portion of suitable diameter and internally threaded, as at g', to screw upon and fit the collar f, as indicated in Fig. 2.

The burner-shell g is formed with an inner tube g², concentric with the outer wall and of such a diameter relatively to the air-draft tube d as will form an annular channel between said parts for the introduction and support of a cylindrical wick i, which may be

vertically adjusted by any approved wick-raising device. (Not shown.) There is a radial flange m extended from the upper edge of the burner-shell g outwardly, terminating in an upwardly-bent edge m', thereby producing a support for the glass lantern-globe B, which latter is of ordinary form and is contracted toward the upper end, which is cylindrical.

The upper end of the draft-tube d is projected a short distance above the concentric wall g² and is closed by a flat cap-plate, the projected portion being numerously perforated at g³ to afford draft and air-escape at the point of combustion.

The flanged supporting-seat m is reticulated between the shell g and upright edge m' to admit air within the globe at this point also.

The frame of the lantern is tubular, comprising two opposite hollow portions n', which are integral with the horizontal draft-pipe n, from the ends of which they depend, and below are bent toward each other, so as to enter apertures oppositely formed in the shell g, which holes are surrounded externally of the burner-shell by the short sleeves n², thereto affixed, into which the lower end portions n³ of the depending members n' are entered and secured.

At the center of the horizontal draft-tube n an inlet is formed, from which a short cylindric neck o depends, terminating in a flaring hood o', that is held above the upper end portion of the globe B, slightly removed therefrom to afford entrance for atmospheric air to the tubular frame for commingling with the gases.

A bail-handle C is loosely attached to the tubular frame of the lantern, as at p, for its convenient portage and manipulation.

In service atmospheric air enters at the base of the fount A, the perforations c permitting this if the lantern is seated upon a flat surface, and passes upwardly through the draft-tube d and issues from the holes g⁴, and as the combustion of the lighted wick i, fed by oil in the fount A, will heat the top of the draft-tube the air is rarefied by contact with it, and in a heated and expanded condition issues directly above the point of combustion,

thereby supplying oxygen to the flame. After proper conditions are established in the lighted lantern the products of combustion will pass upwardly through the neck *o* into the pipe *n*, and thence through its members *n'* downwardly and into the burner-shell *g*, and the unconsumed carbon, mixing with air inducted through the holes in the gallery *m*, is drawn into contact with the flame of the wick *i*, and thus completely consumed, thereby effecting economy in oil consumption and conducing to smokeless combustion within the globe *B*.

Having thus described my invention, what I claim as new, and desire to secure by Letters Patent, is—

As an improved article of manufacture, a central-draft lantern consisting in the annular reservoir *A*, having an apertured support-

ing-flange *b*, a central draft-tube *d*, closed at its upper laterally-foraminated end, and a collar *f*, concentric with and of greater diameter than the tube, the shell *g*, secured upon said neck at *g'* and having an upward extension *g''*, extending adjacent to the upper end of the tube *d* to form the wick-space, the opposite apertured globe-supporting flange or plate *m* on the upper end of the shell, and the tubular frame having inward-bent lower ends *n'*, connected with the opposite sides of the said shell, and the hood *o'* within the upper end of the tubular frame, substantially as set forth.

DANIEL W. CRONIN.
